SEWING MACHINE ATTACHMENT

Charles Seaman, Jamaica Estates, N. Y.

Application April 6, 1943, Serial No. 481,971

18 Claims. (Cl. 112—214)

This invention relates to sewing machines, and particularly to sewing machine attachments.

Prior to this invention, when two or more plies, formed of a single fabric or superposed fabrics, were fed through the stitching position of a sewing machine for the purpose of forming a hem or seam respectively, the upper ply was not fed at the same rate as the lower ply which was in engagement with the feed dogs. Frequently, as a consequence, the lower ply was gathered or puckered more or less haphazardly. This haphazard gathering or puckering is highly undesirable.

In the aforementioned prior art practice, it was essential for the operator to manually control the feeding of the material to be hemmed and at all times carefully and visually observe the folding and stitching operation. If the operation were not so observed, an irregular row of stitches and also sometimes varying widths of hem, in addition to the gathering previously mentioned, would be obtained. As a consequence, a blind individual could not be a successful operator on such work.

An object of this invention is a sewing machine having means to inhibit the gathering of the lower ply of a plurality of plies fed through the stitching position, and which machine can be successfully operated by even a blind operator.

Another object of this invention is to provide a sewing machine attachment which can be quickly and easily attached to the sewing machine without in any way mutilating the machine and which will, when a plurality of plies of a material or materials are fed through the stitching position, inhibit the gathering of the lower ply.

Another object of this invention is to provide an attachment of the type previously mentioned which may be quickly rendered inoperative in the event it is desired not to entirely remove the attachment from the sewing machine.

Other objects will become apparent from the following complete description of the invention.

In general, the objects of one phase of this invention are obtained by providing means to engage and feed the top ply of a plurality of plies of material in the travel thereof to the stitching position at substantially the same linear rate of speed as the lowermost ply is fed by the feed dogs. Other objects of the invention are achieved by providing means to dispose the goods in position for stitching by merely handling the goods without requiring actual observance thereof. The means for feeding the top ply comprises a roll

positioned in advance of the presser foot. The roll is adjustably mounted on an arm adjustably mounted on the presser foot bar whereby it can be adjusted to proper position and will be raised or lowered when the presser foot is raised or lowered respectively. Because of the manner in which the arm carrying the roll is mounted on the presser foot bar, the roll may be raised or lowered as desired, independent of the presser foot bar. The top ply-engaging roll is driven by means driven from the pulley end of the machine, as will be more fully described hereinafter.

In the preferred embodiment of the invention, there is also provided a roll at the rear of the head and cooperating with the work support to engage and feed the material after it has left the stitching position. The roll at the rear of the work support is, as will be hereafter more fully explained, also driven from the pulley end of the machine.

In advance of the stitching position, there is provided means to dispose the goods in position for stitching. This means is provided with a guide whereby, when the raw edge of the goods is manually disposed to abut said guide, the goods will be properly positioned for stitching. The guide is so constructed that the positioning of the raw edge of the goods can be expeditiously and effectively accomplished solely by the hand without the necessity of visually observing the same. Thus, the machine can be successfully operated even by a blind individual.

It will be apparent from the description that the invention can be applied to the stitching together by a single or multiple-needle machine of a plurality of plies formed of the same or different materials, the plies being obtained by folding or superimposition of the goods. For convenience and brevity, the invention will be specifically illustrated and described in connection with producing a hem in which the raw edge is concealed and preferably also secured between a top and bottom ply obtained by folding the goods.

In the drawings,

45 Figure 1 is a top plan view, partly broken away for clarity, of a sewing machine with the attachment positioned in place;

Figure 2 is an end view looking to the left of Figure 1;

50 Figure 3 is an end view looking to the right of Figure 1;

Figure 4 is a section taken on the line 4—4 of Figure 1;

Figure 5 is a perspective of the support and driving mechanism of the attachment; and

Figure 6 is a perspective diagrammatic illustration including the guide and showing the folding of the material and the stitching thereof.

Referring now to the drawings, wherein like reference numerals designate like parts, the reference numeral 10 designates a sewing machine head carried on a base 12. At one end, the head 10 is provided with a needle bar 14 which carries a needle 16. The needle bar 14 is reciprocated by means including a driving shaft 15 which is provided with a pulley 18 in driving relationship thereto. The pulley 18 is driven by a belt 20 from any suitable driving means (not shown). The head 10 is also provided with a presser foot bar 24 which carries a presser foot 26, which operates with feed dogs 28 operated in the usual manner by a four-motion feed drive mechanism (not shown) and passing through slots 30 of a cover plate 32. The presser foot bar 24 can be elevated and lowered by means (not shown) through the manual actuation of the presser foot lever 36. It is to be noted that the needle bar 14 and presser foot bar 24 are on one end of the head 10 and that the pulley 18 and the drive 20 therefor are on the opposite end of the sewing machine head. It will further be observed that the details of the machine thus far described are those of a standard single-needle sewing machine.

In the embodiment shown (see Figure 6), a fabric 38 is rolled to form a two-ply material, the two plies, for purposes of illustration, being designated by the reference numerals 40 and 42. The raw edge of the ply 42 is then rolled inwardly and disposed intermediate the two plies 40 and 42 to constitute a ply 44, in which condition the goods is fed through the path of travel of the needle 16 for stitching.

The fabric 38 is folded into position for stitching, as above described, by means of a folder 46 disposed in advance of the presser foot. The folder 46 is provided with an arm 48, which is carried on an arm pivotally mounted at 50 on a support 52 secured to the base 12 by means of screws 54. In Figure 1, the folder designated in full lines illustrates the folder in operative position; and the folder illustrated in dotted lines illustrates the folder in inoperative position. The folder is secured in position by means of the screws 55 cooperating with the slots 56 and holes (not shown) in the support 52. A pin 57 serves to engage the arm 48 and constitute a stop therefor. To move the folder 46 into inoperative position, the screws 55 are disengaged from the holes in the support 52 and the arm 48 is moved in the appropriate direction about the pivot 50.

The folder 46 is provided with an edge guide control 60 adjacent a curved depression 61, for reasons which will become apparent hereafter.

In operation, the goods 38 is manually folded to form the plies 40 and 42 and, in this condition, fed into the mouth of the folder 46. The lower ply 40 is fed into the mouth, as at 62, and the top ply 42 is positioned on the top of the folder and manually adjusted so that the raw edge thereof is in abutting relationship to the edge guide 60. The folder 46 is of a construction which will roll the raw edge of the original ply 42 and dispose it, as a ply 44, intermediate the top and bottom plies, as above described and as shown in Figure 6.

At the exit end of the folder, there is provided a tongue or guide 63, over which the folded material is fed in its travel from the folder 46 to and through the stitching position. As shown in the

drawings, the guide 63 terminates in close proximity to the presser foot 26.

A roll 66 is disposed in cooperative relationship with the tongue 63 and is adapted to engage and feed the top ply 42 at a linear speed substantially equal to the feed of the lower ply 40 by the feed dogs 28. The roll 66 is rotatably mounted on the lower horizontal member 67 of an arm 68, the upper horizontal member 69 of the arm being rotatably secured in a block 70 adjustably and securely mounted on the presser foot bar 24. The roll 66 is provided with a pulley 72 whereby, upon rotation of said pulley 72, the roll 66 will be rotated. In the specific form shown, the arm 68 for the roll 66 is formed of a single member bent into a form having the lower member 67 and the upper member 69 connected by a vertical member.

The roll 66 is positioned in cooperative relationship with the guide 63 and particularly the forward end thereof is in close proximity to the presser foot. As shown in the drawings (Figure 1), one end of the roll 66 is substantially in alignment with the short member of the presser foot, and the toe of the long member of the presser foot is in a vertical plane which is substantially tangent to or slightly passes through the roll. The roll 66 will also be raised or lowered upon raising or lowering of the presser foot bar 24. The roll 66 can be raised or lowered with respect to the guide 63 by adjusting the position of the block 70 on the presser foot bar 24. The roll 66 can also be adjusted transversely of the guide 63 by positioning the roll on the member 67. As shown in Figure 2, a member 71, secured to the horizontal member 69, is provided with projections 73 and 75 which cooperate with a pin 79. In operative position, the projection 73 is in engagement with the pin 79 and maintained in that position by the tension of an elastic belt 78. Upon rotary movement of the member 69 in the block 70, the roll 66 is moved to inoperative position independent of the presser foot bar 24. In inoperative position, the projection 75 is in engagement with the pin 79 and so maintained by the belt 78.

The roll 66 may be formed of any suitable material, and, in the event the material of which it is formed does not have sufficient tractive force, the latter may be imparted thereto in any convenient manner. A hard rubber roll and a cork roll are illustrative examples of rolls which will give satisfactory results.

In the embodiment shown in the drawings and now being described, there is provided a roll 74 formed of any suitable material and provided with a tractive surface, such as cork. This roll 74 is positioned to the rear of the stitching position and is so disposed that it will engage the stitched material after leaving the stitching position, preferably at the seam thereof, and in cooperation with the work support (base of machine, table, etc.) will feed the material across the work support. The peripheral speed of the roll 74 is substantially equal to the feeding speed of the feed dogs 28.

The roll 74 is secured to a shaft 76 rearwardly of the head and extending transversely of the work support, which shaft, as previously mentioned, is driven from the pulley end of the machine. It is to be noted that a pulley 77 is secured to the shaft 76 and which, by means of a belt 78 formed of an elastic material, such as rubber, drives the pulley 72, thereby imparting rotary motion to the roll 66.

Referring to Figures 1 and 5, a pulley 80 is

secured to a knurled head 19 on the driving pulley 18. The pulley 80 drives a belt 82, preferably formed of an elastic material such as rubber, which drives a pulley 84 secured to one end of a shaft 86. The shaft 86 is rotatably mounted in an arm 90 of a block 92. The other end of the shaft 86 is journaled in the other arm 94 of the block 92. Adjacent the arm 94, the shaft 86 carries a gear 100 which meshes with a gear 102, carried on a stud 104 carried by the arm 94. The stud 104 also carries a gear 106 which meshes with a gear 108 on the end of the shaft 76, which is journaled in the arm 94. The gears 100, 102, 106, 108 constitute a reducing gearing and, by proper selection of the gears, any desired speed of the shaft 76 may be obtained.

Intermediate the arm 94 and the pulley 11, the shaft 76 is provided with a long sleeve 109 which constitutes a protective covering for the shaft.

The block 92 (see Figure 5) is provided with a pair of depending ears 110 through which a shaft 112 extends. The opposite ends of the shaft 112 are journaled in bosses 114 carried by the spaced arms 116 extending from the base 118. Suitable means, such as set screws 120, secure the ends of the shaft 112 in bosses 114. A spring 121 is disposed between collars 122 and 124, one end of the spring being secured to the collar 122 and the other end of the spring being secured to the block 92. The spring normally urges the block 92, which is pivotally mounted on the shaft 112, downwardly.

The base 118 is secured to the work support behind (to the rear) the head by means of screws 130, as shown in Figure 1. Adjacent each end, the base 118 is provided with leveling screws 132, whereby the base 118 may be adjusted (leveled) prior to securing it in place by the screws 130. The leveling screws 132 are provided with washers 134 loosely wedged on the lower ends of the screws and are intended to be disposed intermediate the work support and the bottom of the base 118.

From the foregoing, it is clear that the block 92, which carries the means for driving the shaft 76, is pivotally mounted on the base 118 and that it is continuously urged by the spring 121 to move counterclockwise about the pivot shaft 112, whereby the cork roll 74 will be disposed in cooperative relationship on the work support. When it is desired to remove the cork roll from cooperative relationship with the work support, it (the cork roll 74) is elevated by rotating the block 92 manually clockwise on the pivot shaft 112. The block 92 may be retained in such position by engagement thereof by the top of the curved spring 140, which is secured at its lower end by screws 142 to the base 118. It is pointed out that the drive means for the roll 74 and the manner of rendering the roll 74 inoperative are the same as that described in my application Serial No. 481,972 for "Sewing machine and attachment for preventing accumulation of the work on the work support," filed on April 6, 1943.

It is to be noted that when the cork roll 74 has been disposed in inoperative position, the roll 66 may remain in its operative position or, by rotation of the member 69 in the block 70, may also be moved to inoperative position. When the cork roll 74 is moved to inoperative position and the roll 66 remains in operative position, the latter will be continued to be driven, as previously described. The change in position of the driving mechanism, due to the fact that the belts 78 and 82 are made of elastic material such as rubber,

will not materially interfere with the driving of the roll 66 in operative position when this is desired.

Frequently, in the operation of the machine, the presser foot is elevated or lowered. In the form described, due to the mounting of the roll 66, it (the roll 66) will be given a similar movement. For threading of the goods, it is desirable that the roll 74 also be elevated and rendered ineffective when, for example, the presser foot bar 24 is elevated. With this in view, the shaft 76 is provided with a cap 150 which is non-rotatably freely disposed on the free end of the shaft 76 and rests on the arm 152 of the lift rod 154 to constitute a non-rotatable bearing for the shaft. The upper end of the lift rod 154 is adjustably (slidably) secured by means of a set screw 156 in a block 158 adjustably mounted on and secured to the presser foot bar 24. The lift rod 154 is of such a design that when the presser foot bar 24 is elevated, the arm 152 of the lift rod 154 will elevate the shaft 76, overcoming the force of the spring 121 which urges said shaft downwardly. Upon the lowering of the presser foot, the arm 152 will also be lowered, and the spring 121 through the mechanism hereinbefore described will urge the shaft, and hence the roll 74, downwardly so that it is positioned in operative relationship with the work support.

In operation, the goods 38, folded along one edge thereof to provide the plies 40 and 42, is fed to the folder 46, and the operator, by means of the fingers, positions and maintains the raw edge of the ply 42 in abutting relationship with the guide 60. As long as this condition is maintained, the machine will operate automatically and produce a uniformly stitched seam free of gathers. Since visual observation is not necessary, the machine may be operated by blind individuals. If for some reason or other the roll 66 operates at a greater speed than desired, then the operator by his fingers may exert a pressure on the ply 42 and thereby overcome any undesirable results.

For threading the machine, the presser foot bar 24 is elevated whereby the rolls 66 and 74 will also be elevated and the goods threaded through the folder. After threading, the presser foot is lowered and the machine operated. When it is desired to render the roll 74 inoperative, the block 92 is manually turned on the pivot shaft 112 and locked in position by the spring 140.

Since it is obvious that various changes and modifications may be made in the above description without departing from the nature or spirit thereof, this invention is not restricted thereto except as set forth in the appended claims.

I claim:

1. A sewing machine having a work support, a head, a reciprocating needle bar carrying a needle; means to reciprocate said needle bar including a driving shaft and a pulley in driving relationship to said shaft, said pulley and needle bar being on opposite ends of said head; feed dogs; a presser foot bar carrying a presser foot cooperating with said feed dogs, means to form a plurality of superposed plies of material in advance of the stitching position; a roll in advance of the stitching position to engage and feed the top ply to the presser foot, means carried by said presser foot bar to position said roll in advance of the stitching position; and means driven from the pulley end of said machine to drive said roll continuously during operation of the machine.

2. A sewing machine having a work support, a head, a reciprocating needle bar carrying a

needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, means to form a plurality of superposed plies of material in advance of the stitching position, a roll in advance of the stitching position to engage and feed the top ply to the presser foot, means adjustably carried by said presser foot bar to position said roll in advance of the stitching position, and means driven from the pulley end of said machine to drive said roll continuously during operation of the machine.

3. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, means to form a plurality of superposed plies of material in advance of the stitching position, a roll in advance of the stitching position to engage and feed the top ply to the presser foot, a block on said presser foot bar, a support having one end thereof mounted in said block, said roll being rotatably mounted on the other end of said support, said support being of a design to position said roll in advance of the stitching position but in close proximity to said presser foot, and means driven from the pulley end of said machine to drive said roll continuously during operation of the machine.

4. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot cooperating with said feed dogs, means to form a plurality of superposed plies of material in advance of the stitching position, a roll in advance of the stitching position to engage and feed the top ply to the presser foot, a roll rearwardly of the stitching position and cooperating with the work support to engage the stitched material and advance the same over said work support, means driven from the pulley end of the machine to drive the rearwardly positioned roll, and means connected to said driven means to drive the top ply-engaging roll.

5. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot cooperating with said feed dogs, means to form a plurality of superposed plies of material in advance of the stitching position, a roll in advance of the stitching position to engage and feed the top ply to the presser foot, a shaft rearwardly of the head, a roll mounted on said shaft rearwardly of the stitching position and cooperating with the work support to engage the stitched material and advance the same over said work support, means driven from the pulley end of the machine to drive said shaft, and means driven by said shaft to drive the top ply-engaging roll.

6. A sewing machine having a work support, a head, a reciprocating needle bar carrying a needle, means to reciprocate said needle bar

including a driving shaft and a pulley in driving relationship to said shaft, said pulley and needle bar being on opposite ends of said head, feed dogs, a presser foot bar carrying a presser foot cooperating with said feed dogs, means to form a plurality of superposed plies of material in advance of the stitching position, a roll in advance of the stitching position to engage and feed the top ply to the presser foot, a block on said presser foot bar, a support having one end thereof mounted in said block, said roll being rotatably mounted on the other end of said support, said support being of a design to position said roll in advance of the stitching position but in close proximity to the presser foot, means to mount

said support on said block to permit disposition of said roll in operative or inoperative position, a shaft rearwardly of the head, a roll mounted on said shaft rearwardly of the stitching position and cooperating with the work support to engage the stitching material and advance the same over said work support, means driven from the pulley end of the machine to drive said shaft, and means driven by said shaft to drive the top ply-engaging roll.

7. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, means to form a plurality of superposed plies of material in advance of the stitching position, a roll in advance of the stitching position to engage and feed the top ply to the presser foot, a roll rearwardly of the stitching position and cooperating with the work support to engage the stitching material and advance the same over said work support, means carried by said presser foot bar to elevate said rearwardly positioned roll when the presser foot bar is elevated, means driven from the pulley end of the machine to drive the rearwardly positioned roll, and means connected to said driven means to drive the top ply-engaging roll.

8. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, means to form a plurality of superposed plies of material in advance of the stitching position, a roll in advance of the stitching position to engage and feed the top ply to the presser foot, a block on said presser foot bar, a support having one end thereof mounted in said block, said roll being rotatably mounted on the other end of said support, said support being of a design to position said roll in advance of the stitching position but in close proximity to the presser foot, a shaft rearwardly of the head, a roll mounted on said shaft rearwardly of the stitching position and cooperating with the work support to engage the stitched material and advance the same over said work support, means carried by said presser foot bar to move said shaft and elevate said rearwardly positioned roll when the presser foot bar is elevated, means driven from the pulley end of the machine to drive said shaft, and means driven by said shaft to drive the top ply-engaging roll.

9. A sewing machine having a work support, a

head, a reciprocating needle bar carrying a head, a reciprocating needle bar carrying a needle, means to reciprocate said needle bar including a driving shaft and a pulley in driving relationship to said shaft, said pulley and needle bar being on opposite ends of said head, feed dogs, a presser foot cooperating with said feed dogs, a folder in advance of the stitching position to fold the free edge of the upper ply of the material to be stitched inwardly and dispose it between the upper and lower plies, said folder having a guide at the mouth thereof to engage the free edge and thereby properly position the material and a tongue at the exit end thereof over which the folded material is fed, said tongue terminating in advance of the stitching position and in close proximity to said presser foot, a roll in cooperative relationship with said tongue to engage and feed the top ply to the presser foot, and means driven from the pulley end of said machine to drive said roll continuously during operation of the machine.

10. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, a folder in advance of the stitching position to fold the free edge of the upper ply of the material to be stitched inwardly and dispose it between the upper and lower plies, said folder having a guide at the mouth thereof to engage the free edge and thereby properly position the material and a tongue at the exit end thereof over which the folded material is fed, said tongue terminating in advance of the stitching position and in close proximity to said presser foot, a roll in cooperative relationship with said tongue to engage and feed the top ply to the presser foot, and means carried by said presser foot bar to position said roll in cooperative relationship with said tongue, and means driven from the pulley end of said machine to drive said roll continuously during operation of the machine.

11. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot cooperating with said feed dogs, a folder in advance of the stitching position to fold the free edge of the upper ply of the material to be stitched inwardly and dispose it between the upper and lower plies, said folder having a guide at the mouth thereof to engage the free edge and thereby properly position the material and a tongue at the exit end thereof over which the folded material is fed, said tongue terminating in advance of the stitching position and in close proximity to said presser foot, a roll in cooperative relationship with said tongue to engage and feed the top ply to the presser foot, a roll rearwardly of the stitching position and cooperating with the work support to engage the stitched material and advance the same over said work support, means driven from the pulley end of the machine to drive the rearwardly positioned roll, and means connected to said driven means to drive the top ply-engaging roll.

12. A sewing machine having a work support, a head, a reciprocating needle bar carrying a needle, means to reciprocate said needle bar including a driving shaft and a pulley in driving

relationship to said shaft, said pulley and needle bar being on opposite ends of said head, feed dogs, a presser foot bar carrying a presser foot cooperating with said feed dogs, a folder in advance of the stitching position to fold the free edge of the upper ply of the material to be stitched inwardly and dispose it between the upper and lower plies, said folder having a guide at the mouth thereof to engage the free edge and thereby properly position the material and a tongue at the exit end thereof over which the folded material is fed, said tongue terminating in advance of the stitching position and in close proximity to said presser foot, a roll in cooperative relationship with said tongue to engage and feed the top ply to the presser foot, a roll rearwardly of the stitching position and cooperating with the work support to engage the stitched material and advance the same over said work support, means carried by said presser foot bar to elevate said rearwardly positioned roll when the presser foot bar is elevated, means driven from the pulley end of the machine to drive the rearwardly positioned roll, and means connected to said driven means to drive the top ply-engaging roll.

13. A sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, a folder in advance of the stitching position to fold the free edge of the upper ply of the material to be stitched inwardly and dispose it between the upper and lower plies, said folder having a guide at the mouth thereof to engage the free edge and thereby properly position the material and a tongue at the exit end thereof over which the folded material is fed, said tongue terminating in advance of the stitching position and in close proximity to said presser foot, a roll in cooperative relationship with said tongue to engage and feed the top ply to the presser foot, a block on said presser foot bar, a support having one end thereof mounted in said block, said roll being rotatably mounted on the other end of said support, said support being of a design to position said roll in cooperative relationship with said tongue, a shaft rearwardly of the head, a roll on said shaft positioned rearwardly of the stitching position and cooperating with the work support to engage the stitched material and advance the same over said work support, means driven from the pulley end of the machine to drive said shaft, and means driven by said shaft to drive the top ply-engaging roll.

14. An attachment for a sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, and means to form a plurality of superposed plies of material in advance of the stitching position, said attachment comprising a block to be mounted on said presser foot bar, a support having one end mounted in said block, a roll rotatably mounted on the other end of said support, said support being of a design to position said roll to engage the top ply in advance of the

stitching position but in close proximity to the presser foot, and means to be driven from the pulley end of the head to drive said roll continuously during operation of the machine.

15. An attachment for a sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, and means to form a plurality of superposed plies of material in advance of the stitching position, said attachment comprising a block to be mounted on said presser foot bar, a support having one end mounted in said block, a roll rotatably mounted on the other end of said support, said support being of a design to position said roll to engage the top ply in advance of the stitching position but in close proximity to the presser foot, a shaft to be mounted rearwardly of the head, a roll on said shaft to be positioned rearwardly of the stitching position to engage the stitched material and advance the same over said work support, means to be driven from the pulley end of said machine to drive said shaft, and means driven by said shaft to drive said top ply-engaging roll.

16. An attachment for a sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, and means to form a plurality of superposed plies of material in advance of the stitching position, said attachment comprising a block to be mounted on said presser foot bar, a support having one end thereof rotatably mounted in said block, a roll rotatably mounted on the other end of said support, said support being of a design to position said roll in operative position to engage the top ply in advance of the stitching position but in close proximity to the presser foot, means to mount said support on said block to permit disposition of said roll in operative or inoperative position, a shaft to be mounted rearwardly of the head, a roll on said shaft to be positioned rearwardly of the stitching position to engage the stitched material and advance the same over said work support, means to be driven from the pulley end of said machine to drive said shaft, and means driven by said shaft to drive said top ply-engaging roll.

17. An attachment for a sewing machine having a work support, a head, a reciprocating needle

bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, and means to form a plurality of superposed plies of material in advance of the stitching position, said attachment comprising a block to be mounted on said presser foot bar, a support, a roll rotatably mounted on one end of said support, said support being of a design to position said roll in operative position to engage the top ply in advance of the stitching position but in close proximity to the presser foot, means to mount said support on said block to permit disposition of said roll in operative or inoperative position, a shaft to be mounted rearwardly of the head, a roll on said shaft to be positioned rearwardly of the stitching position to engage the stitched material and advance the same over said work support, means to be mounted on said presser foot bar to engage said shaft and elevate the roll thereon when the presser foot bar is elevated, means to be driven from the pulley end of said machine to drive said shaft, and means driven by said shaft to drive said top ply-engaging roll.

18. An attachment for a sewing machine having a work support, a head, a reciprocating needle bar carrying a needle, means to reciprocate said needle bar including a driving shaft and a pulley in driving relationship to said shaft, said pulley and needle bar being on opposite ends of said head, feed dogs, a presser foot bar carrying a presser foot cooperating with said feed dogs, and means to form a plurality of superposed plies of material in advance of the stitching position, said attachment comprising a block to be mounted on said presser foot bar, a support having one end thereof rotatably mounted in said block, a roll rotatably mounted on the other end of said support, said support being of a design to position said roll in operative position to engage the top ply in advance of the stitching position but in close proximity to the presser foot, means to mount said support on said block to permit disposition of said roll in operative or inoperative position, a shaft to be mounted rearwardly of the head, a roll on said shaft to be positioned rearwardly of the stitching position to engage the stitched material and advance the same over said work support, means to be mounted on said presser foot bar to engage said shaft and elevate the roll thereon when the presser foot bar is elevated, means to be driven from the pulley end of said machine to drive said shaft, and means driven by said shaft to drive said top ply-engaging roll.

CHARLES SEAMAN.

CERTIFICATE OF CORRECTION.

Patent No. 2,378,730.

June 19, 1945.

CHARLES SEAMAN.

It is hereby certified that error appears in the printed specification of the above numbered patent requiring correction as follows: Page 3, second column, line 32, for "operater" read --operator--; page 4, second column, line 21, claim 6 and line 39, claim 7, for "stitching" read --stitched--; and that the said Letters Patent should be read with this correction therein that the same may conform to the record of the case in the Patent Office.

Signed and sealed this 18th day of September, A. D. 1945.

Leslie Frazer

(Seal)

First Assistant Commissioner of Patents.
